UNITED STATES PATENT OFFICE.

JOYCE F. HUDDNALL, OF ACME, WEST VIRGINIA.

COMBINED WIRE STRETCHER AND SPLICER.

Application filed February 18, 1925. Serial No. 10,025.

To all whom it may concern:

Be it known that I, JOYCE F. HUDDNALL, a citizen of the United States, residing at Acme, in the county of Kanawha and State 5 of West Virginia, have invented certain new and useful Improvements in a Combined Wire Stretcher and Splicer, of which the following is a specification.

The present invention appertains to a 10 combined wire stretcher and splicer, and aims to provide a device of simple structure which will be efficient and reliable in connecting the broken ends of wires, such for example, as are used for trolleys. The device 15 is very easy to operate, is strong and durable, and may be manufactured at an exceedingly low cost.

With the above and numerous other objects in view as will appear as the description proceeds the invention resides in certain novel features of construction, and in the combination and arrangement of parts as will be hereinafter more fully described and claimed.

25 In the drawing:—

Figure 1 is a side elevation of the device embodying the features of my invention,

Figure 2 is a top plan view thereof, and

Figure 3 is a transverse section there- 30 through.

Referring to the drawing in detail it will be seen that the body 1 of the device includes a relatively short compartment 2 and a relatively long compartment 3. A pair 35 of screws or bolts 4 are threaded through the top of the compartment 2 in order that a wire may be held in engagement with this end of the body as is indicated in dotted lines in Figure 1. The compartment 3 has

40 the major portion of its top open except for the end as is shown at 5 through which is threaded a bolt 6. The bottom of the compartment 3 has a portion 7 thereof extending parallel with the longitudinal dimension

45 of the body adjacent the outer end thereof and the other portion 8 slanted upwardly therefrom so that a wire may be placed therein and extend through the top as is indicated to advantage by the dotted line showing in Figure 1. The sides of the body 1 adjacent the compartment 3 and over the bottom portion 7 are provided with diagonally arranged registering slots 10 in which is rotatably mounted a shaft 11 having a

50 ratchet 12 formed on a portion thereof exteriorly disposed of the compartment 3 and

adjacent this ratchet a head 13 with which may be easily engaged a suitable tool such as a wrench for turning the shaft. In the compartment 3 there is disposed on the shaft to turn therewith a wheel 14 having diagonally curved teeth thereon. A pawl 15 is pivoted at 16 adjacent the lower end of one slot on one side of the body and is provided with a corrugated lower edge 17 to provide a plurality of teeth for engaging the ratchet 12. This pawl is held in engagement with the ratchet by a spring 18 mounted on the same side of the body as is mounted the pawl.

After one broken end of the wire as is indicated at 20 is engaged in the compartment 2 by the bolts 4, the other broken end of the wire as indicated at 21 is drawn through the compartment 3 under the portion 5 and under the wheel 14. The pawl 15 is then lifted and the shaft slid downwardly in the slots 10 until the wheel 14 engages this end 21 of the wire. A tool such as a wrench may then be engaged with the head 13 so as to turn the shaft 11 and the wheel will draw this end 21 of the wire further into the compartment 3 until the wire has been stretched the desired extent. The slots 10 will wedge the wheel into engagement with the end 21 of the wire during the rotation of the shaft so as to prevent any slipping of the wheel on this end of the wire. When the wire has been stretched to the desired extent the bolt 6 is tightened so as to hold this end 21 in engagement with the body as long as desired. It will be noted that the bottom 22 of the body 1 is rounded as is indicated to advantage in Figure 3 so that the trolley wheel may easily pass over this device.

The construction, operation, and advantages of the invention should now be clearly understood without a more detailed description. The present embodiment of the invention which I have described in detail has merely been given by way of example but the same attains all the features of advantage enumerated as desirable in the statement of the invention and the above description and in practice has been found most efficient. It is to be understood, of course, that numerous changes in the details of construction, in the dimensions, and in the combination and arrangement of parts may be resorted to without departing from the spirit or scope of the invention or without sacrificing any of its advantages.

Having thus described my invention, what I claim as new is:

1. A device of the class described including a body, means at one end of the body for engaging the same with the end of a wire, the other end of the body being provided with a compartment, the sides of said compartment provided with diagonally arranged slots, a shaft journaled through said slots and provided with a ratchet and a head, a pawl pivoted to one side of the compartment, a spring for holding said pawl in engagement with the ratchet, a toothed wheel mounted on the shaft within the compartment, and means for holding the end of a wire after it has been pulled into the compartment by the wheel and shaft all in the manner and for the purpose specified.
2. A device of the class described including a body having a compartment at one end, and a compartment at the other end, bolts threaded into the first compartment for holding a wire engaged therein, the bottom

of said second compartment including a portion extending parallel with the longitudinal dimension of the body and another portion slanting upwardly therefrom, the upper end of said compartment having an opening through which the end of a wire situated in the second mentioned compartment may extend, the sides of said second mentioned compartment being provided with diagonally arranged registering slots, a shaft extending through said slots and having a ratchet and head at one end exteriorly of the compartment, a wheel on the shaft interiorly of the compartment and provided with teeth, a pawl pivoted on one side of the compartment adjacent the ratchet and provided with a corrugated edge for forming a plurality of teeth for engaging the ratchet, a spring pressing said pawl in engagement with the ratchet, and a bolt threaded through the second compartment.

In testimony whereof I affix my signature.
JOYCE F. HUDNALL.
